UNITED STATES PATENT OFFICE

2,054,567

ANIMATED TOY

Charles B. Wincote, San Diego, Calif., assignor of one-third to Cameron A. Peace, San Diego, and one-sixth to Norman D. Mayne and one-sixth to Donald A. Briggs, both of Encinitas, Calif.

Application April 7, 1936, Serial No. 73,074

7 Claims. (Cl. 46—104)

My invention relates to animated toys, and its objects are better to produce characteristic movements of body members in the operation of the toy, to effect such movements at a substantial reduction of wear upon the operative parts, to eliminate jars and bumps in the rotation of the wheels upon which the toy is mounted, to render more lifelike and striking natural movements simulated by the toy, and in general to simplify and render more effective the operation of the several parts.

I am aware that there are now on the market numerous devices constituting toys for the amusement of the young, in which devices the walk and motions of various toy figures are effected. These figures may be actuated by springs or other mechanism, or may be manually operated by pushing or dragging the toy over some surface, such progression serving to cause the toy to perform lifelike, grotesque or amusing movements of the head, arms, wings, tail, legs or other parts thereof. In some of such devices, legs and feet are operated by the wheels upon which the figure is mounted, the rotation of such wheels bringing about a movement of the feet which effectually creates the appearance of walking. These wheeled devices, however, are open to the objection that the rotation of the wheels is often uneven and produces jumps and jars which impair the lifelike simulation of the walk, and which also increases the wear upon the operative parts.

My invention is primarily adapted to be incorporated in a bird-like toy, mounted upon a pair of wheels, which wheels are provided with inclined slots in which are inserted the ends of broad strips of flapping material serving to simulate feet, the forward movement of the toy being effected manually to cause the wheels to revolve and to create the appearance of a lifelike waddling movement.

My invention further consists in the various improvements and novel arrangement of parts illustrated in the drawings and hereinafter described and claimed.

Attention is hereby directed to the drawings in which similar numerals of designation refer to similar parts throughout the several views:

Figure 1 represents a side elevation of a preferred form of my invention;

Fig. 2 is a plan view thereof;

Fig. 3 is a plan view of one of the wheels, showing the central socket and adjacent axle in dotted lines;

Fig. 4 is a view showing in dotted lines the

flopping of the wings through the rotation of the leg flaps.

Referring to the drawings, the body 4 of the toy, here shown in the form of a duck, is made of wood or other suitable material and is mounted upon wheels 7 of similar material. Within slots 10, one of which is formed in each wheel 7 and inclined to the periphery thereof, are thrust broad flat strips of elastic or other suitable material, forming flaps 6, which are shaped and colored to represent legs and feet. To secure the best results, I find it desirable to make the wheels 7 of substantial thickness in order that the slots 10 therein may be of such width and depth as properly to hold and contain the ends 10 of the flaps reposing therein, and to ensure a flat flapping contact of the free ends of said flaps when the same are dashed upon the ground. Preferably, one of these two flaps is attached to one of the wheels circumferentially a little in advance of the point of attachment of the flap on the other wheel, in order that the former flap may touch the ground or floor before the latter, for the purpose of creating the appearance of successive steps. Although I may use tacks, screws or other metallic fastenings in securing either of the flaps within the slots 10, such fastenings may, if desired, be dispensed with and good results secured by merely wedging the ends of the flaps within such slots.

In order that the wheels 7 may be kept in proper alignment, I preferably employ the construction shown in Figs. 2 and 3, whereby the ends of the axle 9 are each firmly held in the sockets 11 by means of the pin 8, offset in the manner indicated. Such construction serves to hold the wheels 7 always in operative position and to co-operate with the flaps 6 to bring about the waddling movement hereinafter referred to. Washers 12 upon the axle 9 serve to keep the wheels 7 in proper spaced relation with the body 4 and to avoid friction therebetween. A stick 13, one end of which engages with the hole 14 in the top of the body 4, is provided as a means for pushing the toy over the floor or ground with which the wheels are in contact. Wings 5 of material similar to the flaps 6 are secured in the groove 15 near the top of the body 4. By inclining the slots 10 of the wheels 7 in the manner shown in the drawings, I am able to furnish a means of smoothly winding the flaps 6 upon the periphery of said wheels, when the same are rotated, until said flaps are cleared from contact with the floor, at which time the free ends of the flaps will spring upwardly and strike 55

against the under surfaces of the wings 5 and thereby cause the same to flop up and down alternately in a lifelike manner. (See Fig. 4.) As the flaps 6 through such rotation are carried further, the free ends thereof will become clear of the wings and will pass over the wheels 7 and descend upon the floor with a pronounced flop and simulate in a realistic manner the well known waddle of a duck or goose.

10 In operating the toy, it is placed in an upright position upon the floor or ground and the stick 13 is grasped firmly in the hand of the operator. Upon the stick 13 being thrust forward, the wheels 7 are caused to revolve, and the flaps 6 made successively to come first in contact with the wings 5 and then to flop upon the ground, thereby causing the figure to proceed with flapping wings and with the appearance of a waddling movement which is lifelike and amusing.

15 20 While I have described and illustrated my invention as embodied in the preferred form above set forth, I by no means desire to limit myself to such form. As is obvious other forms might be employed without departing from the spirit and purpose of my invention. The present embodiment is therefore to be considered, in all respects, as illustrative and not restrictive, the scope of the invention being indicated by the appended claims, rather than by the foregoing description, and all 25 changes which come within the meaning and range of equivalency of any of the elements of the claims are therefore intended to be embraced therein.

What I claim and desire to secure by Letters 30 Patent is:

1. In an animated toy, a figure, wheels upon which said figure is mounted, said wheels being provided with slots inclined to the periphery thereof, combined with flaps engaging with said 35 slots and arranged to simulate body members.
2. In an animated top, a figure, wheels upon which said figure is mounted, said wheels being provided with slots inclined to the periphery thereof, combined with flaps engaging with said

slots and arranged to simulate body members and manual means for actuating said toy and producing an animated appearance of said members.

3. In an animated top, a figure, wheels upon 5 which said figure is mounted, said wheels being provided with slots inclined to the periphery thereof, combined with flaps engaging with said slots and arranged to simulate legs and feet and manual means for actuating said wheels and 10 producing the appearance of walking.

4. In an animated toy, a figure, a pair of wheels upon which said figure is mounted, each of said wheels being provided with a slot inclined to the periphery thereof, and the slot of one wheel being circumferentially in advance of the slot in the other, combined with flaps engaging with said slots and arranged to simulate alternate movements of body members.

5. In an animated toy, the body of a birdlike 20 figure, wheels of substantial width upon which said body is mounted, said wheels being provided with slots of substantial depth and inclined to the periphery thereof, combined with broad flat strips of elastic material the ends of which engage with 25 said slots and leave free broad flapping blades to simulate legs and feet.

6. In an animated toy, an axle, a figure mounted upon said axle, wheels having sockets extending nearly therethrough and being provided with 30 slots inclined to the periphery thereof, said sockets engaging with the ends of said axle and secured thereto by an offset pin combined with flaps engaging with said slots and having the appearance of legs and feet.

7. In an animated toy, a figure, two movable flapping wings attached to said figure, two wheels upon which said figure is mounted, said wheels being provided with slots, two flaps, simulating 40 feet and engaging with said slots, combined with means for causing alternate movements of each of said wings in conjunction with alternate movements of each of said flaps.

What I claim and desire to secure by Letters 30 Patent is:

1. In an animated toy, a figure, wheels upon which said figure is mounted, said wheels being provided with slots inclined to the periphery thereof, combined with flaps engaging with said 35 slots and arranged to simulate body members.
2. In an animated top, a figure, wheels upon which said figure is mounted, said wheels being provided with slots inclined to the periphery thereof, combined with flaps engaging with said

slots and arranged to simulate body members and manual means for actuating said toy and producing an animated appearance of said members.

3. In an animated top, a figure, wheels upon 5 which said figure is mounted, said wheels being provided with slots inclined to the periphery thereof, combined with flaps engaging with said slots and arranged to simulate legs and feet and manual means for actuating said wheels and 10 producing the appearance of walking.

4. In an animated toy, a figure, a pair of wheels upon which said figure is mounted, each of said wheels being provided with a slot inclined to the periphery thereof, and the slot of one wheel being circumferentially in advance of the slot in the other, combined with flaps engaging with said slots and arranged to simulate alternate movements of body members.

5. In an animated toy, the body of a birdlike 20 figure, wheels of substantial width upon which said body is mounted, said wheels being provided with slots of substantial depth and inclined to the periphery thereof, combined with broad flat strips of elastic material the ends of which engage with 25 said slots and leave free broad flapping blades to simulate legs and feet.

6. In an animated toy, an axle, a figure mounted upon said axle, wheels having sockets extending nearly therethrough and being provided with 30 slots inclined to the periphery thereof, said sockets engaging with the ends of said axle and secured thereto by an offset pin combined with flaps engaging with said slots and having the appearance of legs and feet.

7. In an animated toy, a figure, two movable flapping wings attached to said figure, two wheels upon which said figure is mounted, said wheels being provided with slots, two flaps, simulating 40 feet and engaging with said slots, combined with means for causing alternate movements of each of said wings in conjunction with alternate movements of each of said flaps.
